UNITED STATES PATENT OFFICE.

VICTOR H. LATENDORF, OF BAYONNE, NEW JERSEY.

AEROPLANE.

1,034,257.

Specification of Letters Patent. Patented July 30, 1912.

Application filed April 5, 1910. Serial No. 553,523.

To all whom it may concern:

Be it known that I, VICTOR H. LATENDORF, having declared my intention of becoming a citizen of the United States, and resident of Bayonne, county of Hudson and State of New Jersey, have invented certain new and useful Improvements in Aeroplanes, of which the following is a specification.

This invention relates to air-ships, and 10 more particularly to the type of heavier-than-air machines usually called aeroplanes.

The improvements constituting the invention are particularly, though by no means exclusively, adapted to the mono-plane form 15 of aeroplane.

The object of the invention is to produce an aeroplane presenting wings which will closely reproduce the qualities of the wings of soaring birds, with a view to securing 20 the best results in the way of sustaining power and stability.

Further objects of the invention will appear as the specification proceeds.

To these ends, the invention consists in the 25 parts, arrangements and combinations hereinafter described and in the claims more particularly pointed out.

The accompanying drawings illustrate 30 what is believed to be the best form of the invention; but it should be understood that many, apparently different, embodiments of the invention may be constructed without departing from the scope thereof.

In these views, wherein similar characters of reference indicate similar parts in all the figures: Figure 1 is a side elevation of the aeroplane; Fig. 2 is a sectional elevation taken on the line 2—2 of Fig. 1; Fig. 3 is a 35 plan view of the aeroplane, showing the rudder and the stabilizing surfaces in mid-position; Fig. 4 is a plan view, showing the rudder moved to one side and the stabilizing surface at that side projected; Fig. 5 is a detail elevation on an enlarged scale of 40 the parts for supporting and actuating the stabilizing surfaces; one of the stabilizing surfaces being shown in vertical cross-section; Fig. 6 is a longitudinal sectional elevation 45 of the parts at the forward part of the aeroplane; Fig. 7 is a perspective view of the raising and lowering planes and immediately connected parts; and Figs. 8 and 9 are two views at right angles showing one 50 of the frame members.

In these views, the numeral 10 indicates a supporting plane, consisting of two wings

11 and 12. These wings extend outward and slightly upward from a longitudinal median line, which median line, in the best form of the invention, dips gradually to the rear, as clearly shown in Fig. 1. These wings will usually be made of canvas or other flexible material stretched between frame members, the preferred arrangement of which will now be described. A central 60 longitudinal frame member 13, which defines the median line referred to, extends from front to rear of the plane and is slightly arched. In accordance with the invention it is arranged so that from a point 65 in rear of its front end, but materially nearer said front end than its rear end, it is directed, gradually downward to the rear. This frame member 13 may be formed of two strips 14 arranged side by side, as 70 shown in Fig. 4. Side frame members 15 diverge rearward from the front end of the central frame member 13; the front ends of 75 these three frame members being suitably united together in any usual or approved 80 manner. In accordance with the best embodiment of the invention, these side frame members 15 are bowed or curved slightly, in an outward and upward direction, that is, their curves lie in inclined planes. The rear 85 ends of the side frame members 15 are connected with the rear end of the central frame member 12 by rear frame members 16, which converge rearward. These members 90 16 are straight in the best form of the invention. The angle between these rear frame members 16 is materially greater than the angle between the side frame members 15. When the wings are completed by stretching the canvas or similar material 95 between the frame members as described, and particularly when the aeroplane is in motion, with the canvas somewhat bellied upward under the air pressure, they closely correspond in action to the wings of soaring 100 birds. The side members 15 may be connected with the central frame member 13 by straight brace members 17.

A propeller 18 may be mounted on the plane 10 at either end thereof, or may be 105 supported or mounted in any suitable or approved manner. It is shown as being driven by a motor 19, which is supported on a platform 20 for the operator. This platform may be supported from the plane by 110 a suitable number of standards 21 and 22. The standard 21 is shown as constituting a

mast, which extends through the plane 10 on the median line thereof, being preferably secured to and between the strips 14 of the central frame member 13. In accordance with the form of the invention illustrated, this mast is located in advance of the longitudinal center of the plane. It serves as the support for a pivoted rudder 23. As shown, this rudder has its vertical rudder surface disposed over the rear part of the plane 10, and is connected pivotally with the mast 21 by long supporting rods 24. Means are provided for moving the rudder from the platform 20; and such means may comprise cords or ropes 25 secured to the rudder and extending therefrom to pulleys 26 secured to the side frame members 15, thence to pulleys 27 mounted on the plane near the median line thereof, and thence passing through the plane downward to a hand-wheel 28. Obviously, such means may be widely varied. I provide a stabilizing plane 28, which is moved automatically with the movement of the rudder. The construction, arrangement and particular mode of actuation of such stabilizing plane may be widely varied. As shown, it comprises two stabilizing surfaces 28, 28, which are connected by a rope wire, or other means, 29 to move together. These stabilizing surfaces may, however, be distinct. These surfaces 28 are shown as mounted to slide transversely beneath the plane 10 in a suitable guide frame, comprising channeled slide-ways 30 and depending supporting standards 31. In the illustrated construction, these surfaces 28 are connected to move with the rudder, by means of ropes or other flexible connections 32, which are secured to and extend from the inner ends of the surfaces 28 over pulleys 33 to the hand-wheel 28. Thus, it will be seen, when the rudder 23 is swung to one side or the other, the stabilizing surface 28 at that side is projected. Raising and lowering planes 34 may be located at either end of the plane, and preferably above the same. As shown, two such planes, spaced transversely from each other, are supported over the front part of the plane 10, at opposite sides of the median line thereof. They may be secured to opposite ends of a tilting frame 35, journaled on a transverse axis in a bracket 36 secured to the frame member 13. This frame may comprise three parallel rods, a rod 37 which is journaled in the bracket 36, and top and bottom rods 38, to which may be secured operating ropes or the like 43, which extend to an operating wheel 39 on the platform. The ends of the rods 37 and 38 may be connected by brace rods 40, and brace rods or ropes 41 may connect the ends of these rods 40 with the front and rear edges of the planes 34. In passing downward to the operating wheel 39, the ropes 43 may pass over

pulleys 44. Suitable guy-ropes or the like 45 are shown connecting the several angles of the plane 10 with the mast 21. A guy rope 47 may connect the outer end of the rudder with the mast.

In operation, the aeroplane, by reason of its peculiar and bird-like construction of wings, will be found to have great lifting power for its size, and exceptional stability. When the rudder is swung to one side or other, tendency of the plane to tip to that side is neutralized by the transverse shifting of the stabilizer. The aeroplane may rest upon the ground upon wheels 46, for the purpose of securing a running start.

Having thus described my invention, what I claim as new, and desire to secure by Letters Patent, is:

1. In an aeroplane, a supporting plane consisting of two wings having a central longitudinal junction and thence extended outward and slightly upward to diverging side edges, said side edges extending rearward from the front of said junction and being disposed at a slightly greater elevation than said junction, and rear edges converging from the rear ends of said side edges to the rear end of said junction, the angle between said rear edges being materially greater than the angle between said side edges.

2. In an aeroplane, a supporting plane consisting of two wings having a central longitudinal junction which is slightly arched and the major and rear portion of which extends gradually downward, said wings extending from said junction outward and slightly upward to diverging side edges which extend rearward from the front of said junction at a slightly greater elevation than said junction, said side edges being slightly curved outward and upward, and straight rear edges converging from the rear ends of said side edges to the rear end of said junction, the angle between said rear edges being materially greater than the angle between said side edges.

3. In an aeroplane, a supporting plane comprising a central longitudinal frame member directed gradually downward and curving toward the rear, diverging side frame members extending rearward and curving from the front of said central frame member and disposed at a slightly greater elevation, rear frame members connecting the rear ends of said central and side frame members, and material supported by said frame members and constituting wing surfaces.

4. In an aeroplane, a supporting plane comprising a central longitudinal frame member which, from a point in rear of its front end but materially nearer its front than its rear end, extends gradually downward and curving to the rear, diverging side

frame members extending rearward and curving from the front of said central frame member and disposed at a slightly greater elevation, and rear frame members connecting the rear ends of said central and said side frame members, and material stretched between said frame members and constituting wing surfaces which extend outward and slightly upward from said central frame member.

5. In an aeroplane, a supporting plane comprising a central longitudinal frame member which is arched and from its forward portion extends gradually downward to the rear, diverging side frame members extending rearward from the front of said central frame member and disposed at a slightly greater elevation, said side frame members being curved outward, rear frame members converging from the rear ends of said side frame members to the rear end of said central frame member, the angle between said rear frame members being materially greater than the angle between said side members, and material stretched between said frame members and constituting symmetrical, bird-like wing surfaces.

6. In an aeroplane, a supporting plane comprising a central longitudinal frame member which is arched and is directed gradually downward from its forward portion to its rear, diverging side frame members extending rearward from the front of said central frame member and disposed at a slightly greater elevation, said side frame members being curved outward and upward, rear frame members converging rearward from the rear ends of said side frame members to the rear end of said central frame member, the angle between said rear frame members being materially greater than the angle between said side members, and material stretched between said frame members and presenting symmetrical, bird-like wing surfaces.

7. In an aeroplane, a supporting plane comprising a central longitudinal frame member which is arched and is directed gradually downward from its forward portion to its rear, diverging side frame members extending rearward from a point at the front of said central frame member and

disposed at a slightly greater elevation, said side frame members being curved outward, straight rear frame members converging rearward from the rear ends of said side frame members to the rear end of said central frame member, and material stretched between said frame members and presenting two symmetrical wing surfaces.

8. In an aeroplane, a supporting plane comprising a central longitudinal frame member which is arched and is directed gradually downward from its forward portion to its rear, diverging side frame members extending rearward from a point at the front of said central frame member and disposed at a slightly greater elevation, said side frame members being curved outward, straight rear frame members converging rearward from the rear ends of said side frame members to the rear end of said central frame member, material stretched between said frame members and presenting two bird-like wing surfaces, and straight brace members connecting the side frame members with the central frame member intermediate their ends.

9. In an aeroplane, the combination of a supporting plane consisting of two symmetrical wings extended outward and slightly upward with reference to a longitudinal median line, a vertical mast extended upward from the forward part of said plane on said median line, and a vertical rudder pivoted to said mast and extended therefrom over the rear portion of the plane.

10. In an aeroplane, the combination of a supporting plane consisting of two symmetrical wings extended outward and slightly upward with reference to a longitudinal median line which has a slight dip to the rear, a vertical mast extended upward from the forward part of said plane on said median line, and a vertical rudder surface located over the rear of said plane, and supporting rods connecting said rudder surface pivotally to said mast.

Signed in the city, county and State of New York, this 26th day of March, 1910.
